SUPERSTRUCTURE UNIT FOR VENDING MOTOR VEHICLES

Thomas Carvel, Chauncey, N.Y.

Application August 8, 1958, Serial No. 52,117

Term of patent 14 years

(Cl. D14—27)

Fig. 1

Fig. 2

Fig. 3

Fig. 4

Fig. 1 is a plan view of the superstructure unit for vending motor vehicles, showing my new design;

Fig. 2 is a side elevation thereof seen from the right side of the structure;

Fig. 3 is a front elevation of the structure; and

Fig. 4 is a rear view thereof.

I claim:

The ornamental design for a superstructure unit for vending motor vehicles, substantially as shown.
